UNITED STATES PATENT OFFICE.

MAURICE D. BROWN, OF YONKERS, AND HAROLD K. BEACH, OF HASTINGS-UPON-HUDSON, NEW YORK.

BRAIDING-MACHINE.

965,437.

Specification of Letters Patent. Patented July 26, 1910.

Application filed February 10, 1910. Serial No. 543,055.

To all whom it may concern:

Be it known that we, MAURICE D. BROWN and HAROLD K. BEACH, citizens of the United States, residing, respectively, at Yonkers and at Hastings-upon-Hudson, in the county of Westchester and State of New York, have invented a new and useful Improvement in 5 Braiding-Machines; and we do hereby declare the following, when taken in connection with the accompanying drawings and the characters of reference marked thereon, to be a full, clear, and exact description of the same, and which said drawings constitute part of this specification, and represented, in—

Figure 1 a broken top or plan view of a portion of a braiding machine illustrating our invention. Fig. 2 a vertical sectional view on the line *a—b* of Fig. 1. Fig. 3 a 20 broken sectional view on the line *c—d* of Fig. 1. Fig. 4 a plan view of one of the operating levers, detached. Fig. 5 a plan view of one of the in and out blocks, detached.

25 This invention relates to an improvement in braiding machines especially intended for covering wire for electric use, but which may be used, if desired, without a wire or core so as to produce a tubular body.

30 The object of the invention is a simple and convenient means for moving the spindles, and the invention consists in the particular arrangement of parts as will be hereinafter described and particularly recited 35 in the claims.

In carrying out our invention we employ two plates 2 and 3 arranged in the same plane. These are so mounted and arranged as to form an annular slot 4 between them.

40 In these plates are a series of radially aligned slots 5 in which are mounted in and out blocks 6 carrying spindles 7 on which bobbins 8 are mounted, the blocks being adapted to slide from one plate into the 45 other plate. Below the plates 2 and 3 is a rotary plate 9, and this lower plate 9 carries a series of spindles 10 which extend through the slot 4 so as to travel therein, as the plate 9 is turned. Threads from bobbins 11 carried by the said plate 9 pass up through 50 these spindles. Pivotaly mounted on each spindle 10 beneath the plates 2 and 3 is a lever 12 having a long forwardly projecting nose 13 and at the rear with a left arm 14

and a right arm 15 for the purpose as will 55 hereinafter appear.

Any convenient means may be provided for driving the rotary plate 9. As this plate advances, the nose 13 will engage with the block 6 located in the plate 2 and backed up 60 by a pin 16 mounted in the under face of the plate 2, as indicated in position *a* will crowd the block from the plate 2 into the plate 3, and as it continues in its course the right arm 15 will engage the block which is then 65 in the plate 3 and swing the lever from the position *a* to the position *b*, the extent of throw being limited by a stop-pin 17 in the under face of the plate 3. The lever is then in position to engage with the next block in 70 the plate 3 and move that next block from plate 3 to plate 2, and as it continues its movement the left arm 14 will engage the pin 16 and turn the lever to its first position. Thus the threads from the movable bobbins 75 will be woven with threads from the bobbins carried by the block 6, and these threads are carried up and around a core or wire entered through a centrally arranged opening 18 as common with braiding machines. 80

We claim:

1. In a braiding machine, the combination with two upper plates arranged in line and spaced to form an annular slot between them, said plates being also provided with 85 radial slots, in and out blocks adapted to slide in said slots from one plate to the other, spindles carried by said blocks, a rotary plate below said upper plates carrying a series of spindles extending upward through said 90 slot, a swinging lever mounted on each moving spindle, said lever comprising a forwardly projecting nose, and right and left arms by which the in and out blocks are moved from one plate to the other alternating 95 with the movements of the rotary moving spindles.

2. In a braiding machine, the combination with two upper plates arranged in line and spaced to form an annular slot between them, said plates being also provided with radial slots, in and out blocks adapted to slide in said slots from one plate to the other, spindles carried by said blocks, a rotary plate below said upper plates carrying 100 a series of spindles extending upward through said slot, a swinging lever mounted on each moving spindle, said lever comprising 105

ing a forwardly projecting nose, right and left arms by which the in and out spindles are moved from one plate to the other alternating with the movements of the rotary moving spindles, and stop pins in the under face of said upper plates to limit the movement of said levers.

In testimony whereof, we, have signed

this specification in the presence of two subscribing witnesses.

MAURICE D. BROWN.
HAROLD K. BEACH.
